UNITED STATES PATENT OFFICE.

HARRY E. TREAT, OF ROCHESTER, NEW YORK.

SHOEMAKER'S LAST.

Application filed July 2, 1920. Serial No. 393,667.

To all whom it may concern:

Be it known that I, HARRY EDWIN TREAT, a citizen of the United States, residing at Rochester, in the county of Monroe and 5 State of New York, have invented certain new and useful Improvements in Shoemakers' Lasts, of which the following is a specification.

This invention relates to improvements 10 in shoemakers' wooden lasts and constitutes a further development of the ideas disclosed in my copending application filed October 4, 1919, Serial No. 328,421.

The ordinary wooden last is of one piece 15 construction, at least so far as the body of the last is concerned, and after the toe portion of such a last has become considerably worn, this being the part which receives the greatest wear and strain, the entire last is 20 discarded. Likewise when fashion decrees a change in the styles of shoes, the old style lasts are usually discarded even though they may be comparatively new and in good 25 condition. Therefore it is one of the primary objects of the present invention to disclose a means whereby lasts which would otherwise be discarded may be repaired or made over by the substitution of a new toe 30 portion to replace a worn or damaged toe portion or to provide a toe portion of a different shape, or if desired the invention may be practiced by originally manufacturing a last in accordance therewith.

A further object of the invention is to 35 provide means whereby not only may the general shape of the toe portion of a last be changed, in carrying out the invention, but also if desired a change may be made in the shape of the side portions of the last 40 immediately in advance of the instep.

Another object of the invention is to provide means whereby a last originally manufactured, subsequently repaired, or reconstructed in accordance with the principles 45 of the invention by the substitution of a new toe portion, may have the said portion effectually braced and its connection with the body portion of the last materially strengthened and reinforced so that the last 50 will be as solid as a one piece last.

The invention also contemplates the union, with the body portion of a last, of a toe portion having its grain running longitudinally and substantially parallel to the 55 working face of the last and in this respect the invention effects a decided improvement

over the ordinary one piece wooden last in which the grain runs diagonally to the working face of the toe portion and in the use of which latter type of last the toe portion is extremely liable to be broken or chipped off while in use. 60

In the accompanying drawings:

Figure 1 is a perspective view of one form of last constructed in accordance with the 65 present invention;

Fig. 2 is a bottom plan view of the last;

Fig. 3 is a side elevation of the forward part of the last;

Fig. 4 is a perspective view partly in 70 section illustrating a modified form of last;

Fig. 5 is a bottom plan view of the last shown in Fig. 4;

Fig. 6 is a view similar to Fig. 5 illustrating one type of means which may be employed for reinforcing the connection between the toe and body portion of the last; 75

Fig. 7 is a view similar to Fig. 6 illustrating a further modification;

Fig. 8 is a side elevation of the fore part 80 of the last shown in Fig. 7.

In all figures of the drawings, the body portion of the last is indicated in general by the numeral 1 and the toe portion by the 85 numeral 2 and, so far as the present invention is concerned, the body portion 1 may be of any desired contour and of any desired construction. However, in that form of the invention shown in Figs. 1, 2 and 3 of the drawings, for the purposes of the present 90

invention, the body portion 1 is formed with a blunt forward end 3 which may be produced either by initially forming the body of the last minus the toe portion or by cutting off the toe portion from an ordinary 95 wooden last the original toe portion of

which has become damaged or is considered to be out of style. In this form of the invention the body portion 1 of the last is formed substantially midway between its opposite sides, with a vertical mortise 4 which extends inwardly from the blunt or squared forward end 3 of the said body portion 1, and the opposite sides of the body portion at its forward end are mortised or recessed 105 one as indicated by the numeral 5 and the other as indicated by the numeral 6. The recess or mortise 5 is formed in the outer side of the last and the recess or mortise 6 in the inner side thereof whether the last be 110 designed for use in the manufacture of a right or a left shoe. Therefore the recess 5

is or may be somewhat longer than the recess 6. In any event the recesses will preferably open through the under or working face of the body portion of the last and also 5 through the respective side faces of the last.

Likewise in this form of the invention the toe portion 2 is formed with a relatively blunt rear end 7 and is provided with an integral intermediate tenon 8 and side tenons 10 one indicated by the numeral 9 and the other by the numeral 10. The tenons 8, 9 and 10 are respectively fashioned and proportioned to fit snugly within the mortises or recesses 4, 5 and 6 as most clearly shown in Fig. 2 15 of the drawings and as regards the tenons 9 and 10, it will be observed that the same completely fill the recesses or mortises 5 and 6 and that the outer and under surfaces of these tenons merge and form continuations 20 of the corresponding surfaces of the toe portion 2. At this point it may be stated that these tenons 9 and 10 are employed chiefly for the purpose of affording means whereby the shape of the shoe to be manufactured 25 may be changed and with this end in view the outer sides of the said tenons may be of any desired contour or initially formed somewhat larger than desired and then cut down to the required shape or form.

30 Any suitable means may be employed for the purpose of securing the tenons in their respective mortises. If the toe portion is intended to be removably secured in place, screws or the like will be utilized as securing 35 means but if the toe portion is to be permanently united to the body portion, I preferably make use of dowels as illustrated in the said Figs. 1, 2 and 3. Thus the tenon 8 may be secured by two dowel pins 11 placed 40 at its opposite sides and driven into place at any desired angle of inclination as for example as shown in Fig. 3 of the drawings in dotted lines, and these pins may be of wood or metal or any other suitable material. By reference to Fig. 2 it will be observed that the pins 11 seat substantially half in the opposite faces of the tenon 8 and substantially half in the opposing walls of the mortise 4. Likewise dowel pins 12 and 45 13 are employed for the purpose of securing the tenons 9 and 10 in the respective recesses or mortises 5 and 6 as shown in Fig. 2 and it will be understood that glue may be employed between the surfaces to effect more 50 secure union in cases where the toe portion is to be permanently united to the body portion.

55 As above stated the tenons 9 and 10 are employed primarily to afford means whereby the contour of the opposite sides of the last may be varied but if this is neither required nor desired, these tenons and their respective mortises may be omitted and I may employ the single tenon 8 for the purpose of uniting 60 the toe portion to the body portion.

In that form of the invention shown in Figs. 4 and 5 of the drawings, the body portion 1 of the last is formed in its forward end with spaced mortises 14 and the toe portion 2 is provided or formed with 70 spaced tenons 15 which are disposed to fit within the mortises 14. In this form instead of using dowel pins extending to a considerable depth in the last, I may form one wall of each mortise 14 with a recess 75 16 and may form the opposing face of the respective tenon 15 with a recess 17, and then upon assemblage of the toe portion with the body portion and upon registration of the corresponding recesses 16 and 80 17, may fit or drive into place a small rectangular block 18 of wood, metal or any other material to perform the same function as that performed by the dowel pins heretofore described. 85

Instead of employing two or more mortise and tenon joints between the toe portion and body portion of the last as shown in Figs. 4 and 5 of the drawings, I may employ but a single mortise, and tenon joint 90 as illustrated in Fig. 6, the mortise of this figure being indicated by the numeral 19 and the tenon by the numeral 20. Likewise in this form of the invention I may make use of a key block 21 corresponding 95 to the blocks 18 heretofore described. Where, however, but a single tenon is made use of, I find it desirable to provide an additional bracing means between the toe and body of the last and I may accomplish 100 this result by forming a socket 22 in each side of the last partly within the rear or inner face of the toe portion 2 and partly within the forward end face of the body portion 1, and in each of these sockets I 105 fit or drive a short dowel 23.

Instead of employing the dowel 23 which is preferably cylindrical in form, I may make use of a key such as shown in Figs. 7 and 8 of the drawings and indicated by the 110 numeral 24, this key being preferably in the nature of an approximately semi-circular flat sided piece of metal which may be driven into correspondingly formed recesses 25 in the meeting ends of the toe and body 115 portions of the last.

Having thus described the invention, what is claimed as new is:

1. A shoemaker's last comprising a body portion and a toe portion each having a 120 blunt end, the blunt end of one of said portions being recessed to form a mortise and the blunt end of the other being provided with an integral tenon fitting the mortise, and a locking element seated within a recess 125 formed partly in one side of the tenon and partly within the confronting wall of the mortise, the mortise and tenon being disposed substantially perpendicularly to the working face of the last and extending lon- 130

5 gitudinally with relation to their respective portions, and the locking element being co-extensive in height with the tenon and extending from the working face of and heightwise of the last and having its lower end disposed substantially flush with said working face.

2. A shoemaker's last comprising a body portion and a toe portion, one of said 10 portions being formed with a mortise and the other with a tenon fitting

the mortise, the two said portions at one side being formed at their juncture with registering recesses, and a locking element seating in the said recesses and spanning 15 the juncture, the mortise and tenon extending longitudinally with relation to their respective portions, and the locking element extending approximately parallel to the working face of the last.

In testimony whereof I affix my signature.

HARRY E. TREAT.
